(57) **CLAIM**

The ornamental design for a cell phone keychain attachment, as shown and described.

DESCRIPTION

FIG. 1 is a front perspective view of a cell phone keychain attachment.

FIG. 2 is a front view of the cell phone keychain attachment shown in FIG. 1.

FIG. 3 is a rear view of cell phone keychain attachment shown in FIG. 1.

FIG. 4 is a left side view of the cell phone keychain attachment shown in FIG. 1.

FIG. 5 is a right side view of the cell phone keychain attachment shown in FIG. 1.

FIG. 6 is a top view of the cell phone keychain attachment shown in FIG. 1.

FIG. 7 is a bottom view of the cell phone keychain attachment shown in FIG. 1.

FIG. 8 is a perspective view of the cell phone keychain attachment attached inside on a side of a phone case showing that the cell phone keychain attachment can be sandwiched between the phone case and the phone; and,

FIG. 9 is a perspective view of the cell phone keychain attachment attached thorough a side opening in a side of a phone case showing that the cell phone keychain attachment can be sandwiched between the phone case and the phone. The dotted line disclosure forms no part of the claimed invention.

The break in the lines indicate indeterminate length.

1 Claim, 7 Drawing Sheets
